(57) **CLAIM**

The ornamental design for a suction cup apparatus holder, as shown and described.

DESCRIPTION

FIG. 1 is a perspective view of a suction cup apparatus holder showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 and FIG. 9 are perspective views of the suction cup apparatus holder showing states of use thereof.

The broken line showing illustrates portions of the suction cup apparatus holder that form no part of the claimed design.

1 Claim, 9 Drawing Sheets
